UNITED STATES PATENT OFFICE.

ALBERT FALK, OF NEW YORK, N. Y., ASSIGNOR TO FALK TOBACCO COMPANY, OF NEW YORK, N. Y.

DESIGN FOR A LABEL-BLANK.

45,376.

Specification for Design.

Patented Mar. 10, 1914.

Application filed December 13, 1913. Serial No. 806,639. Term of patent 7 years.

To all whom it may concern:

Be it known that I, ALBERT FALK, a citizen of the United States, residing at New York, in the county of New York and State of New York, have invented a certain new, original, and ornamental Design for a Label-Blank, of which the following is a specification, reference being had to the accompanying drawing, forming a part thereof.

The figure is a plan view of a label blank showing my new design.

I claim:

The ornamental design for a label blank, as shown.

ALBERT FALK.
